CLAIM

The ornamental design for a telephone, as shown and described.

DESCRIPTION

FIG. 1 is a front elevational view of a telephone showing our new design;

FIGS. 2 and 3 are respectively left and right side elevational views thereof;

FIG. 4 is a rear elevational view thereof; and

FIGS. 5 and 6 are respectively top and bottom plan views thereof.

The telephone of this invention is characterized by a pair of praying hands.
